LIGHTING FIXTURE

Filed June 17, 1929

Abraham Lazerson
Gillson, name of
Otto

UNITED STATES PATENT OFFICE

ABRAHAM LAZERSON, OF CHICAGO, ILLINOIS

LIGHTING FIXTURE

Application filed June 17, 1929. Serial No. 371,425.

This invention relates to an improved form of semi-indirect lighting fixtures, and has for one of its prime objects the provision of interchangeable parts so as to permit of ready assemblage, convenience in shipping, and low cost of repair.

Another object contemplates the provision of a form of lighting fixture which, because of its composite character, may be made up into fixtures having various ornate appearances, all of which have grace and are pleasing to the eye.

These and other objects will appear when read in conjunction with the following drawings, in which

Fig. 1 is a side elevational view of one embodiment of this invention, with parts in section and parts broken away;

Fig. 2 is a bottom view of a fixture comprising four glass flutes;

Fig. 3 is a section on the line 3—3 of Fig. 1;

Fig. 4 is an elevation of one of the standards, with parts broken away;

Fig. 5 is an elevation of the cross brace member;

Fig. 6 is a side view of the attaching plate;

Fig. 7 is a vertical section of the base plate;

Fig. 8 is an elevation of the cap;

Fig. 9 is an elevation of the securing nut and associated part;

Fig. 10 is a side elevation of one of the flute members; and

Fig. 11 is a bottom view of a fixture comprising three flutes.

In the manufacture of electric light fixtures it is desirable that means be provided for producing a variety of designs from a plurality of units of the same construction. This arrangement permits the manufacturer to standardize on his production to a great extent, and at the same time an almost infinite variety of designs may be built up from these units. In the form of construction selected to illustrate an embodiment of the invention, the flute members and standards or flute supports are identical whether the lamp fixture be provided with only two or with a greater number of these units, thus permitting the use of a single mould for the flutes irrespective of the design of the chandelier.

This is considered a very important feature of the invention, because it makes it possible to produce a great variety of designs at a minimum of time, labor and expense in the manufacture and installation of the different constructions or designs.

Furthermore, where the designs are all different and contain no parts in common, as is the present practice, the dealer, in order to supply his customers, must keep an adequate supply of each type in stock which amounts to a considerable outlay in the aggregate.

With the present invention the dealer is enabled to supply his customers with fixtures without the necessity of keeping such a large supply on hand because of his ability to build up the different designs from units that are common to all of his designs.

Referring now to the drawings, the fixture comprises a ceiling plate 10, a central supporting member or shank 11 having a threaded portion 12 at its lower end. A plate 13 is mounted on the shank 11, and is held in place by the nut 14. This nut is provided with a transverse opening 30, through which the electric conductors for the light bulbs extend. The plate 13 has dependent lugs 15 at its corners and sockets 16 on its upper face and intermediate the lugs.

Standards or flute supports 17 are secured at their bases to the dependent lugs 15 of the plate 13 by the screws 18. These standards are ornate and are rabbeted, as at 19, to receive flutes 20, and are braced and positioned by the straps 21 which are preferably of metal. Medial stays 22, preferably ornamental in appearance, may be provided for engaging the outer surface of the flutes. These stays are rigidly mounted on the brace members 21, and extend longitudinally of the flutes and assist in positioning the same. The flutes are reduced at their lower ends for forming shoulders or ribs 23 for engaging the strap 21. One of the flutes 20 and a co-operating support or standard 17 constitute what may be termed a unit since these members are common to all designs or forms of construction.

A cross brace 24 is mounted on the shank 11, the arms of which are fastened in any

25 suitable manner at 25 to the standards 17, giving great rigidity to the fixture. A base plate or husk 26 encloses the bottom portions of the standards and flutes and gives a finished appearance to the fixture.

5 The lower portion of the nut 14 is tapped to receive a threaded rod 110 on the lower portion of which the cap 27 is threaded for holding the base plate or husk 26 in place.

10 The wiring of the fixture is not shown but may be carried down the interior of the shank 11 and out through the opening 30 in the nut 14, where suitable connections are made to the sockets 16 which carry the lamp bulbs 28 in the usual manner.

15 To make up a four-fluted fixture the ceiling plate 10 and the shank 11 are first put in place, the cross brace 24 and the socket plate 13 are mounted on the end of the shank 11, and a nut 14 is screwed into place to hold them on the shank. The standards 17 are then fastened to the lugs 15 of the socket plate 13 which, for a four-fluted fixture, is quadrangular. Thereupon the straps 21, with their integral medial stays 22, are secured to the standards, the cross brace 24 is then screwed to the standards, the base plate or husk 26 is drawn up, and the cap 27 screwed onto the shank 11 to hold it in its place. The lamp bulbs 28 may now be inserted in their sockets and the flutes 20 dropped into position between the standards. The lamp sockets are so arranged that the bulbs 28 will be located within the flutes, there preferably being one bulb for each flute.

20 In order to make up a fixture having any other number of flutes, all that is necessary is to substitute for the socket plate 13 a similar plate having the requisite number of sides and make corresponding changes in the cross brace 24 and the base plate or husk 26. It will thus be seen that a fixture of any number of flutes may be built by the use of the proper socket plates, cross braces and base plates.

25 It will also be understood that the fixture may be modified so as to adapt it for use on a wall bracket, the means for supporting the single glass flute being substantially the same as that disclosed for the ceiling fixture, viz:—two rabbeted edges and a strap engaging the ribbed portion of the single flute.

30 By reason of the structure of this invention it is possible to ship the parts separately and the fixture can easily be made up during its installation. Furthermore, because of its composite character different ornamental appearances may be achieved by the use of a varying number of flutes.

35 It will be understood that the invention is susceptible of various modifications and changes without departing from the spirit of the invention as expressed in the appended claims forming a part hereof.

40 I claim as my invention:

1. In a lighting fixture, a translucent flute curved in cross-section and flared at its upper end, said flute having its lower end reduced to form a shoulder for engaging a strap support and having its side edges in a common plane whereby the same are adapted to engage the rabbeted edges of supporting standards. 70

2. A composite lighting fixture comprising, in combination, standards angularly positioned about a central supporting member and having rabbeted edges, translucent flutes curved in cross-section mounted between the standards and having their side edges engaging said rabbets, and means for holding said flutes in place. 75

3. A composite lighting fixture comprising, in combination, standards angularly positioned about a central supporting member and having rabbeted side edges, and translucent flutes adapted to be dropped into place between the said standards with their side edges engaging said rabbets, said flutes having a reduced lower portion, and straps extending between said standards for engaging said reduced portions for holding said flutes in position. 85

4. A composite lighting fixture comprising, in combination, standards angularly positioned about a central supporting member, translucent flutes mounted between the standards, and means comprising a strap extending between adjacent standards for supporting the outer surface of the said flutes, and against which said flutes are held by gravity. 90

5. A composite lighting fixture comprising, in combination, standards angularly positioned about a central supporting member, translucent flutes mounted between the standards, and means comprising a strap extending between adjacent standards for engaging the outer surface of the said flutes for supporting the same, said straps having medial stays in aid thereof. 105

6. A composite lighting fixture comprising, in combination, standards angularly positioned about a central supporting member, translucent flutes mounted between the standards, each flute being provided with a rib extending transversely thereof, and means comprising a strap extending between adjacent standards for supporting the outer surface of the said flutes and adapted to fit against the ribbed portion of the said flutes. 115

7. In a composite lighting fixture, the combination of a shank, a socket plate mounted on said shank, standards mounted on said socket plate, straps extending between adjacent standards, and translucent flutes adapted to be fitted between the said standards, said straps engaging said flutes above the lower ends thereof for detachably supporting the same. 120

8. A lighting fixture comprising, in combination, a shank threaded at its lower end, 125

- a socket plate adapted to be loosely mounted on said shank and held in place by a nut on the lower end of the shank, standards mounted on the socket plate, straps between adjacent standards, translucent flutes adapted to be fitted between the standards and supported by the straps, and a husk adapted to be mounted on the shank and held in place by a cap.
- 5 9. A lighting fixture comprising, in combination, a shank threaded at its lower end, a socket plate adapted to be loosely mounted on said shank and held in place by a nut on the lower end of the shank, standards mounted on the socket plate, cross braces between 10 the standards, straps between adjacent standards, translucent flutes adapted to be fitted between the standards and supported by the straps, and a husk adapted to be mounted on the shank and held in place by a cap.
- 15 10. A unit for building up a light fixture from a multi-unit structure of a lesser number of units to one of a greater number of units, which comprises a flute supporting member having rabbeted side edges, a flute member of frangible material having one edge seated in said rabbet, and a strap member secured to said support and extending about said flute member for holding the same 20 in engagement with said rabbet.
- 25 11. A unit for building up a light fixture from a multi-unit structure of a lesser number of units to one of a greater number of units, which comprises a flute engaging standard, means on said standard for attaching 30 the same to a multi-unit socket plate, said plate tapering toward its attaching end and provided with a recess extending along each of its side edges, a flute member having one edge seated in one of said recesses, said flute member tapered toward the attaching end of 35 said standard, and means engaging said flute for supporting the same with its side edge in said recess.
- 40

In witness whereof I affix my signature.

45 ABRAHAM LAZERSON.
